(57) **CLAIM**

The ornamental design for a radio frequency identification (RFID) reader, as shown and described.

DESCRIPTION

FIG. 1 is a perspective view of a radio frequency identification (RFID) reader showing our new design; FIG. 2 is a front elevation view thereof; FIG. 3 is a rear elevation view thereof; FIG. 4 is a left side view thereof; FIG. 5 is a right side view thereof; FIG. 6 is a top plan view thereof; FIG. 7 is a bottom plan view thereof; FIG. 8 is another perspective view thereof, showing a state in which a grip portion of the RFID reader has been rotated; and, FIG. 9 is another perspective view thereof, showing a state in which an antenna part of the RFID reader has been protruded from a main body.
